UNITED STATES PATENT OFFICE.

EUGENE F. LOWE, OF DELEVAN, NEW YORK.

NUT-LOCK.

1,204,798.

Specification of Letters Patent. Patented Nov. 14, 1916.

Original application filed November 17, 1915, Serial No. 61,963. Divided and this application filed December 21, 1915. Serial No. 68,023.

To all whom it may concern:

Be it known that I, EUGENE F. LOWE, a citizen of the United States, residing at Delevan, in the county of Cattaraugus and State of New York, have invented certain new and useful Improvements in Nut-Locks, of which the following is a specification, reference being had to the accompanying drawings.

10 My invention relates to means for preventing the accidental unscrewing of nuts or bolts, and particularly to a means peculiarly designed for use in connection with the rail chairs such as are shown in my 15 pending application for patent Serial No. 61,963, filed November 17, 1915, on rail chair and joint, of which application this present application is a division.

The general object of my invention is the 20 provision of means which will prevent the accidental unscrewing of nuts on those bolts which form primary fastenings for rail chairs, this means, however, permitting the ready removal and replacement of the nut 25 or nuts whenever desired.

Still another object of the invention is to provide a nut locking or holding means of such form that vibration incident to the travel of trains over rails will not cause the 30 nut holding or locking means to shift from its operative engagement with the nut or nuts.

Another object is to provide means of this character which shall be very simple, easily 35 manipulated, easily applied, and very effective in action.

My invention is illustrated in the accompanying drawings, wherein:

Figure 1 is an elevation, partly in section, 40 of a portion of a tie having a rail chair provided with my improved nut locking devices; Fig. 2 is a section on the line 2-2 of Fig. 1.

Referring to these drawings, B designates a rail and A a tie upon which the rail is mounted. As illustrated, the rail B is mounted in a chair 10 having under-cut end flanges, and rail-engaging members 11 are disposed between these end flanges and the 50 rail and engage over the base of the rail. These rail-engaging members 11 as illustrated are each formed with a longitudinally extending recess 12 having a flat upper face, the rail-engaging members and the chair being bored for the passage of vertically dis-

posed bolts 13 which pass through the tie and operatively engage therewith. The bolts are screw threaded at their upper ends for the reception of nuts 14, and the object of the present invention is to provide means 60 for holding these nuts in place.

To this end the side wall 15 of the recess 12 is formed at spaced intervals with inwardly extending bores 16 and disposed in each bore is a coiled spring 17 which bears 65 outward on a locking head 18. This head is shouldered at its middle to provide a portion embraced by the end of the springs and a stud which is engageable with an opening formed in a transversely extending strip 19. This strip 19 has a length equal to that of the corresponding rail engaging member 11, and this strip, it will be seen, is resiliently urged outward at its opposite ends and against the flat side faces of the 70 nuts 14. After the nuts have been turned down to engage the work, the heads 18 will be forced inward by any suitable means, as by an implement fitted for the purpose, and the strip 19 dropped into place between the 75 faces of the nuts and the face of the recess 12. The strip 19 is formed with perforations 20 into which the studs on the heads 18 are adapted to engage as illustrated in the drawing so that when the strip 19 is 80 forced into place the studs on the heads 18 will automatically spring into these perforations 20 as soon as the strip has reached its proper position, thus locking the strip 19 in place and preventing any movement 85 of the strip until the heads 18 have been forced rearward. When it is desired to release either pair of nuts 15, the locking heads 18 are forced inward by any suitable 90 means, as for instance, a nail, and the strip withdrawn. This permits the nuts to be 95 turned in a reverse direction.

While I have illustrated my invention as applied to a particular form of rail-engaging member, and while it is peculiarly adapted to the conditions of railway service, yet I do not wish to be limited to this application as it is obvious that other locking devices of the same character and operating on the same principle may be used in a large variety of circumstances. One reason why my improved device is peculiarly adapted for railway service is that the vibration caused by passing trains will not affect the locking heads 18 because of the cushioning 100 105 110

effect of the springs 17. These springs, furthermore, always force the plate 20 against the nuts 14. Furthermore, inasmuch as this plate 20 has preferably a thickness equal to the distance between the flat face of the nut and the face of the recess 12, it is obvious that the nut cannot possibly become unscrewed.

It will be seen that the means for holding the strip 19 in place is to a large extent concealed so that there is no surface offered to mischievously inclined persons to remove the locking device. Furthermore, it is very readily possible to so form the perforations 20 in the strip 19 that a peculiarly formed implement would have to be used in order to be inserted through the strip and engage the heads 18.

Having described my invention, what I claim is:

1. The combination with a body having a bolt perforation, said body having a face extending parallel to the bolt perforation and spaced therefrom, a bolt passing through said perforation, a nut mounted on the bolt, a member disposed between a side of the nut and the adjacent face of the body and preventing rotation of the nut, and a resiliently actuated member operatively engaging the nut-locking member and holding it in place, the body having a recess within which said resiliently actuated member is positively housed.

2. The combination with a body having a bolt perforation, said body having a face extending parallel to the bolt perforation and spaced therefrom, a bolt passing through said perforation, a nut mounted on the bolt, a member disposed between the side of the nut and the adjacent face of the body and preventing rotation of the nut, and means for holding said member in place, said means including a resiliently actuated locking stud mounted upon the body and engaging with the perforations in the plate.

3. The combination with a body having a bolt perforation and formed with a face extending parallel to the perforation and with bores extending inward from said face, of a bolt passing through the perforation and having a nut, a member disposed between the nut and the said face of the body and preventing the rotation of the nut when in place, said member having a recess upon its inner face, a spring disposed in each bore, and a locking stud outwardly urged by the spring and adapted to engage in the corresponding perforation of said member.

4. The combination with a nut and bolt, of a body having a face disposed parallel to a side of the nut, a perforated member disposed between the nut and said face and preventing the rotation of the nut, and an outwardly urged locking stud mounted upon said body and adapted to be projected into the perforation in said member to lock it in place.

5. The combination with a body having a bolt perforation formed with a wall having a face extending parallel to the axis of the perforation, of a bolt passing through the perforation, and a nut therein having its side face disposed opposite said wall, a member removably disposed between the face of the nut and the face of the wall and preventing the rotation of the nut, said member being perforated at a plurality of points, the wall being formed with a plurality of bores, coiled springs disposed in the bores and heads mounted upon said coiled springs and having studs smaller than the heads and adapted to be received in said perforations and lock the member in place.

In testimony whereof I hereunto affix my signature in the presence of two witnesses.

EUGENE F. LOWE.
